UNITED STATES PATENT OFFICE.

ARTHUR E. SPARROW, OF CHICAGO, ILLINOIS.

DESIGN FOR A COMBINED STOP LIGHT, TAIL LIGHT, AND DIRECTION SIGNAL.

Application filed February 23, 1922. Serial No. 840. Term of patent 3½ years.

To all whom it may concern:

Be it known that I, ARTHUR E. SPARROW, a citizen of the United States, residing in the city of Chicago, in the county of Cook and the State of Illinois, have invented a new, original, and ornamental Design for a Combined Stop Light, Tail Light, and Direction Signal, of which the following is a specification, reference being had to the accompanying drawings, forming a part thereof.

In the drawings:—

Figure 1 is a face view or elevation showing my new design.

Figure 2 is a top plan view of the same.

I claim:—

The ornamental design for a combined stop light, tail light, and direction signal.

In testimony whereof, I have hereunto set my hand at Chicago, Illinois, this 21st day of February, 1922.

ARTHUR E. SPARROW.
